MANUFACTURE OF REWOVEN CARPET

Charles Robert McGimsey, Rowayton, Conn.

Application November 17, 1937, Serial No. 175,007

7 Claims. (Cl. 28—1)

This invention relates to the manufacture of rewoven carpet, and more particularly to a method of producing rewoven carpet from old cut pile carpet. Although the term "cut pile carpet" should be clear to those of skill in the art, it may be explained that by that term I mean carpet wherein the pile threads are cut or come to an end at the top or outer surface of the carpet, being usually arranged in so-called "pile-V's" which are each looped at the apex over a weft thread and held between adjacent warp threads of the carpet base. Cut pile carpets include, for example, the weaves known as velvet, Wilton, or Axminster, and are thus to be distinguished from what I shall call the closed type of carpet weave, wherein each nap thread or yarn is continuous across or lengthwise of the fabric, as exemplified by the carpet weaves known in ingrain, body, Brussels, or tapestry.

For reasons of economy, it is often desired to reweave old rugs or other pieces of carpet into a new carpet, which may be of different dimensions and which may have an all-over color representing the colors of the old carpet used, or may be dyed or carefully woven to present new patterns or colors; much saving can be made by thus utilizing old carpet, which may be worn, faded, torn or otherwise practically useless. In the case of old rugs of the closed carpet weave, such as those hereinabove mentioned, it is a relatively simple process to use the material comprising the yarns and threads of the old rug, for reweaving; but in cut pile carpets the pile yarn consists of a multitude of short and often loosely twisted pieces which naturally separate as such, so that direct methods are ineffective or uneconomical to derive weft for reweaving, from old rugs of the cut pile type.

One method of employing the material in old cut pile carpet to make new rugs or other carpet has involved the use of a machine which breaks up the old carpet material and reduces it to a mass of very short, substantially untwisted yarn fibres. They must then be put through a regular spinning process, as if they were fresh unspun wool, to re-create a continuous yarn, and that, with other threads, subjected to a preliminary weaving operation, to produce the fluffy weft employed in the ultimate production of the "re-woven" carpet. That weft, however, is very light and sleazy, and hence a "filler" weft must also be employed in weaving the carpet. This filler is usually twisted paper, or a heavy strand of sized jute; and as a result, if it is later attempted to wash or clean the re-

woven carpet, such paper becomes soft, or if jute is used, the sizing is dissolved, and the carpet or rug becomes limp and lacking in sufficient body to rest on a floor satisfactorily. Furthermore, there is no way to restore the firmness of the carpet, since the filler wefts are so closely associated with the pile weft, that sizing or the like cannot be reintroduced in the filler.

Among other objects, the present invention has for its purpose the avoidance of complex and relatively costly procedure, such as that just outlined, for re-weaving old cut-pile carpet. Another important object of the invention is to provide a simple, economical and rapid method for producing re-woven carpet from old cut-pile carpet; to provide such a method which may be carried out without specialized complex apparatus, and with a minimum of labor and attention; to provide, as a result of such method, a re-woven carpet of remarkable durability and particularly pleasing appearance; and to provide for the production of a firm, full-bodied re-woven carpet which may be cleaned or washed many times without injury to its body, firmness, or other characteristics. Other objects and advantages will be hereinafter mentioned or will become apparent as the invention is described.

Referring to the drawing, which illustrates certain stages in a preferred embodiment of the invention,

Fig. 1 is a perspective view of the old carpet as passed between a pair of rolls for the treatment step of the method, and

Fig. 2 shows a narrow strip of the treated old carpet, partly twisted for use in reweaving.

In carrying out the invention in the manner which is in part illustrated in the drawing, the old cut pile carpet 10, preferably after it has been swept or otherwise cleaned, is passed between a pair of rolls 11, 12, and latex 13 is forced into the backing or ground of the carpet from what is normally the floor side of the latter. The latex 13 may be conveniently applied to the surface of one of the rolls 11 by an apertured conduit 14 fed from a hopper 15. Thus naturally spreading over the surface of roll 11, the latex forms an even liquid sheet which engages, and is impregnated into, the backing side of the carpet 10; or the arrangement may be conveniently such that the latex is poured directly into and along the V between the back of the carpet 10 and the roller 11.

Before the latex-treating step, the old carpet, or particularly its under side, is preferably wet with water, not only to make it pliable and more

easily worked, but to facilitate the absorption of latex by the backing fibers of the carpet, and afford an economy in the amount of latex required for satisfactory results.

- 5 After the old carpet has been treated with latex as described, so that the backing, and particularly the interstices between the ground threads thereof and the apexes of the pile-V's, have been permeated with the liquid rubber material, the carpet may be allowed to rest for a period, usually only a few hours, so as to effect at least some setting or oxidization of the latex. Thereupon the treated carpet may be cut up into narrow strips, say one-half inch or less in width, which are eventually tied together to make the weft that will constitute the nap in the ultimate rewoven rug.

As shown in Fig. 2, the strip 20 thus cut from the old carpet is preferably twisted (as shown at 20 21) throughout its length, so that the final element consists essentially of a strong central core from which radiates a cylindrical brush of yarn fibres. It will now be appreciated that any such division of the original old carpet into strip, even 25 without any attempt at twisting, would cause a great deal of the cut pile to fall out; but with the latex treatment as described the cut pile tufts or V's are tenaciously held by the resulting deposit or film of rubber, to the backing threads, 30 and the latter (both warp and weft) are held together as well as in engagement with the base of each pile tuft. Consequently the old carpet may not only be effectively divided into relatively narrow strips, but the latter may be twisted as 35 tightly or as loosely as desired, without any loss of the pile fibres at all,—even in the case of portions of an old carpet where the pile has worn very short or has been partly worn away, or where the backing has worn thin or loose, or 40 where the backing has been broken or dry-rotted (as by drying at too high a temperature after cleaning). It is believed that the cutting of the latex-treated carpet, and the twisting of the strips, may be advantageously carried out before 45 the latex has completely set,—thus tending to make the strip retain its twisted shape naturally, after the latex has fully set.

If the twisted strips are too short to be satisfactorily introduced, for example, as weft elements in the ultimate reweaving process, it will 50 be understood that they may be tied, spun or otherwise fastened together to make up longer strips. The strips may be, if desired, cut from the old carpet with the cutting devices which 55 have been previously used for dividing up closed weave carpet, such as Brussels, for reweaving, and which are provided with opposing toothed rollers that engage opposite sides of the strip to work it and make it fluffy. With the present 60 method, however, the last mentioned parts need not be used in many cases, since the cut pile of the original old carpet usually affords ample "fluffiness"; in addition, the strips may be much narrower, and a closer weave employed for re- 65 weaving, so that although the weft made of the strips may have less body, the finally rewoven carpet has a more compact, uniform and plush-like surface than hitherto attainable in any rewoven carpet. Furthermore, the strips need not, 70 as is generally the case in preparing to reweave Brussels or like closed-weave carpet, be cut parallel to the warp threads; they can be conveniently cut the longer way of the rug, whether along warp or weft, or along a diagonal.

75 The final step of my method is then to utilize

the treated carpet strip, preferably twisted in the manner described, to weave the "rewoven" carpet. Although other weaves may be employed, I prefer to use the described strip or strips as weft in producing carpet of the type called reversible chenille (or fluff rugs), i. e., having what is generally known as a Smyrna weave. After weaving, it is generally not necessary to operate on the fabric by a shearing machine of the type used upon previous types of rewoven carpet, since the pile or nap surface of the described carpet is pleasingly uniform and even. The resulting rewoven carpet is very durable, and has a soft but closely compacted surface of remarkably pleasing appearance; furthermore, it may be repeatedly washed or otherwise cleaned without injury to its body, firmness or other desirable characteristics.

By way of specific example, I have obtained good results using, for the treating step of the 20 process, a composition made up of three parts by volume of a commercially available 77% latex (viz., 77% rubber) and one part by volume of water. Other proportions may of course be used, and the rubber material impregnated into the 25 backing in other ways than by squeezing between rolls; it being chiefly important to obtain a strongly adhesive but readily resilient impregnation of the backing without appreciable overflow into the standing part of the pile yarn. Instead 30 of ordinary latex, there may be used other settable liquid rubber materials, in the form of solutions, dispersion, rubber cements, or the like, or substitutes or equivalents therefor. The treating liquid, such as the latex solution specifically 35 referred to, may also include dyes or coloring matter, so that for example the backing alone is dyed, and can only show in the ultimately rewoven carpet as darker than or of the same color as the nap,—in accordance with the dye so used. 40 In that way, the resulting rewoven rug may be made to have a more uniform and even color, than carpet rewoven according to the prior methods hereinabove described.

It will be understood that the invention is not 45 limited to the specific procedure and materials herein illustrated and described, but may be carried out in other ways without departure from its spirit as defined by the following claims.

I claim:

1. Method of producing rewoven carpet from old cut pile carpet, comprising causing liquid rubber material to set in the base of the old cut pile carpet, dividing the carpet material into strip form, and utilizing said strip, with the pile tufts 55 held in the base thereof by the set rubber material, in weaving carpet.

2. Method of producing rewoven carpet from old cut pile carpet, comprising introducing settable liquid rubber material into the base of the 60 old cut pile carpet, and thereafter weaving carpet with narrow strip cut from the old carpet and having the pile tufts held in the base of the strip by the rubber material set therein.

3. Method of producing rewoven carpet from 65 old cut pile carpet, comprising impregnating the base of the old cut pile carpet with settable liquid rubber material, dividing the treated carpet into narrow strip form having the pile tufts retained in the base of the strip by the setting of the rubber material therein, twisting the strip, and weaving carpet with the twisted strip material as a 70 nap-forming element therefor.

4. Method of producing rewoven carpet from old cut pile carpet, comprising causing liquid rub- 75

ber material to set in the base of the old cut pile carpet, dividing the carpet material into strip form and twisting the strip, to provide a nap-forming element wherein the pile tufts are held in the twisted base by the rubber material, and utilizing said element as weft in weaving carpet.

5. Method of producing rewoven carpet from old cut pile carpet, comprising treating the base of the old cut pile carpet with settable liquid rubber material and causing said material to set partially therein, cutting the treated carpet into narrow strip form and twisting the strip before the rubber material has fully set, and after said material has fully set, weaving carpet with said

15 strip as a nap-forming element.

6. Method of producing rewoven carpet from old cut pile carpet, comprising impregnating the base of the old cut pile carpet with a settable

liquid rubber material, dividing said impregnated carpet into narrow strips after the rubber material has set to prevent displacement of the cut pile from said strips, and without removing the pile from the base in the strips, weaving a carpet 5 wherein the strips are used for weft.

7. Method of producing rewoven carpet from old cut pile carpet, comprising pressing a settable liquid rubber material into the base of the old cut pile carpet from the under side thereof, permitting said rubber material to set at least partially, cutting the treated old carpet to provide a weft comprising the old carpet material in strip form with the pile held to the base by the rubber material, and utilizing said weft in weaving 10 15 carpet.
